UNITED STATES PATENT OFFICE.

CHARLES L. HOPKINS, OF RIVER FOREST, ILLINOIS, ASSIGNOR TO BENJAMIN ELECTRIC MANUFACTURING COMPANY, OF CHICAGO, ILLINOIS, A CORPORATION OF ILLINOIS.

ELECTRIC SWITCH.

Application filed October 18, 1919. Serial No. 331,624.

My invention relates to electric switches.

One of the objects of my invention is to provide an improved switch in which two breaks are made in the circuit substantially simultaneously, thereby dividing and decreasing the arcing effect, and consequently lessening the danger of injury to the switch, and other undesirable effects.

A further object of my invention is to provide an electric switch for use in an electrical receptacle, which will be simple in construction, and efficient in use, and cheap to manufacture.

Further objects will appear from the detailed description to follow and from the appended claims.

In the drawings, in which two embodiments of my invention are shown:

Fig. 1 is a plan view of a pull switch socket embodying my invention;

Fig. 2 is a section on the line 2—2 of Fig. 1;

Fig. 3 is a section on the line 3—3 of Fig. 2;

Fig. 4 is a section substantially on the line 4—4 of Fig. 1;

Fig. 5 is a section substantially on the line 5—5 of Fig. 2;

Fig. 6 is a section substantially on the line 6—7 of Fig. 1 looking to the left;

Fig. 7 is a section substantially on the line 6—7 of Fig. 1 looking to the right;

Fig. 8 is a detail perspective view showing part of the switch frame;

Fig. 9 is a detail perspective view showing a combined bearing and spring retaining member;

Fig. 10 is a detail perspective view of one of the rotatably mounted switch contacts;

Fig. 11 is a detail perspective view of a fixed spring contact member forming part of the switch;

Fig. 12 is a plan view showing another form of my invention embodied in a pull switch socket;

Fig. 13 is a section on the line 13—13 of Fig. 12;

Fig. 14 is a section on the line 14—14 of Fig. 13;

Fig. 15 is a section substantially on the line 15—15 of Fig. 12;

Fig. 16 is a section substantially on the line 16—17 of Fig. 12 looking to the left;

Fig. 17 is a section substantially on the

line 16—17 of Fig. 12 looking to the right; 55

Fig. 18 is a detail perspective view of a fixed spring contact member forming part of the switch;

Fig. 19 is a detail perspective view showing a combined bearing and spring retaining member; and 60

Fig. 20 is an exploded perspective view of certain parts of the switch.

In order to give a general idea of the construction of Figs. 1—11 inclusive, it is 65

here stated that my invention is here shown embodied in a pull switch socket, having shell and center contacts, 25 and 26 respectively, for engagement with an insertable device of the Edison type and having wiring 70

terminals 27 and 28 for connection with a pair of feed wires, (one of the wiring terminals 27 being connected directly with the threaded shell contact of the receptacle), and a pull switch mechanism having two rotatably mounted contacts 29 and 30 (in- 75

sulated from each other in the "off" position), one of these contacts 30 being electrically connected with the center contact, and the other contact 29 being electrically 80

connected with the other wiring terminal 28, and a relatively stationary electrical conducting member 30^a with which the two rotatable contacts 29 and 30 both make contact in their movement, and with respect to 85

which both of said contacts are movable out of contact in their movement, whereby as the contacts are rotated, the circuit from the wiring terminal to the center contact is broken at two points, substantially simultaneously. 90

The receptacle contacts, switch mechanism and wiring terminals are all mounted on an insulating base 31, and this insulating base and parts carried thereby are housed 95

in a sheet metal casing 32 having a sheet metal cap 33, which can be removed for wiring, repair, etc. The usual lining 34 of insulating material, such as fibre or the like, is provided between the shell contact 25 100

and the casing 32, and a cover 35 of suitable insulating material, as fibre, is provided above the insulating base 31 to prevent short circuiting of the live parts carried by the insulating base. 105

The wiring terminal 27 is electrically connected with the threaded shell contact 25 by means of a screw 36 (Figs. 1 and 3) the

head of which engages the flange 37 of the threaded shell contact, and the upper end of which is threaded into the wiring terminal 27. The wiring terminal 28 is secured 5 on the insulating base 31 by means of a screw 37^a (Figs. 1 and 3). The wiring terminals 27 and 28 are provided with the usual binding screws 38.

The pull switch mechanism comprises (in 10 addition to the two separated rotatably mounted contacts 29 and the connecting member 30, previously referred to), a rotatably mounted insulating contact-carrier 39 to which the contacts 29 are secured, (the 15 contact-carrier, together with the contacts carried thereby forming a commutator member), an oscillatable operating member or switch-lever 40, which is operated to impart movement to the commutator, ratchet mechanism 41 between the oscillatable lever 40 and the commutator for changing the oscillating movement of the switch lever 40 to a step by step movement in the commutator, a pull chain 42 carried by a chain-rail 43 for 20 operating the switch lever 40, and a coil torsion spring 44 for returning the switch lever 40 after it has been operated by the pull chain 42.

A shaft 45 is secured to the contact-carrier 30. This shaft may be molded into the contact-carrier if desired. One end of this shaft is rotatably mounted in a combined bearing and spring retaining member 46 which is adjustably secured in an opening 47 35 in a bracket 48. This bracket 48 is secured in place on the insulating base 31 by means of a screw 49, which screw also serves to electrically connect this bracket 48 with the center contact 26. The contact 30 is electrically connected with the shaft 45 by means 40 of an arm or connecting member 50, which extends inwardly from the contact, and surrounds the shaft 45, this shaft 45 being of conducting material, so that the contact 30 45 is always electrically connected with the center contact 26 through the screw 49, the bracket 48, the shaft 45, and the arm 50.

This arm 50 is also provided with ratchet teeth 51 which form part of the ratchet mechanism 41 between the switch lever 40 and the commutator, the switch lever 40 being provided with depressions 52 for cooperating with the ratchet teeth 51. These depressions 52 have sloping bottoms, which slope 55 down from the surface of the lever 40, terminating against the shoulders 53, against which the free ends of the ratchet members 51 engage when the switch lever 40 is rotated. These depressions 52 may be formed 60 in the lever 40 in the operation of stamping, the lever 40 being made from sheet fibre, which is of such a nature that these depressions can be formed by stamping. The chain-rail 43 may be a sheet metal stamping, 65 having a curved arcuate portion 54 in which

the chain lies, and having a hook portion 55 for engagement with one of the balls of the chain 42, whereby the chain is secured to the chain-rail. The chain-rail is secured to the switch lever 40 by means of integral projections 57 (Figs. 2 and 7) which extend through openings in the lever 40, the ends of these lugs being bent over to firmly secure the chain-rail in place.

One end of the torsion spring 44 is secured to the switch lever 40 as shown in Figs. 2 and 4, the end of the spring engaging a lug 58, and the other end of the spring is secured to a lug 59 (Figs. 1 and 9) formed integral with this bearing and spring 70 securing member 46. For adjustably securing this bearing and spring member in the bracket 48, for adjusting the tension of the torsion spring 44, the member is provided with a struck-up portion, or lug 60 (Figs. 2 and 9) which struck-up portion can be made to engage in any one of three slots 61, extending outwardly from the opening 47 in the bracket 48 (Fig. 8), the member 46 is provided with a slot 61^a for engagement with a screw-driver, whereby the member 46 can be pushed inwardly and turned to the desired position, and then allowed to spring out again, (under the action of the spring 44) to cause the lug 60 to again engage one 85 of the slots 61. As previously stated, the purpose of this torsion spring 44 is the return to switch lever 40 after it has been operated by the pull chain 42. It also exerts endwise pressure to keep the ratchet 100 members in engagement. Pulling down on the chain 42 revolves the commutator through the ratchet mechanism 41. After the chain has been pulled down, it is released, and the torsion spring 44 returns the switch 105 lever 40 and pull chain 42 to their original positions, the commutator, however, remaining stationary during this return movement, the ratchet mechanism 41 permitting this 110 return movement of the switch lever 40 without a corresponding movement of the commutator.

The binding terminal 28 has a bracket portion 62 formed integral therewith, which has an opening which provides a bearing for one end of the commutator. The contact 29 is electrically connected with this bracket portion 62 by means of an arm 63 (Figs. 5 and 10) extending inwardly from the contact, this arm 63 being provided with a sleeve 115 portion 64 which fits snugly in an opening in the bracket portion 62, and in which sleeve 64 an extension 65 of the contact-carrier 39 fits snugly (Figs. 2 and 5). The contact 29 is thus always in electrical connection with the wiring terminal 28 thru the arm 63, sleeve portion 64 and bracket portion 62.

As previously described, the other rotatable contact 30 is always in electrical con- 130

nection with the center contact. In the "off" position of the switch, these two rotary contacts 29 and 30 are insulated from each other, but in the "on" position of the switch they are electrically connected with each other through the connecting member 30^a. The circuit from the wiring terminal 28 to the center contact is thus made and broken at two points simultaneously by moving the contacts 29 and 30 into and out of contact with respect to the connecting member 30^a. This connecting member 30^a, (Figs. 1, 6 and 11) is preferably made of a single piece of spring material such as 15 spring brass or bronze, and comprises a base portion 66 (secured to the insulating base 31 by means of a screw 67) and a pair of spring contact fingers 68 and 68^a respectively, the contact finger 68 being located 20 so that the contact 29 can be moved into and out of engagement, and the contact finger 68^a being located so that the contact 30 can be moved into and out of engagement therewith, by rotating the commutator. 25 The contact carrier 39 is provided with a central flange portion 70, which forms an insulating barrier and serves to prevent short circuiting or arcing between the contacts 29 and 30. Each of the contacts 29 30 and 30 is spirally curved to conform to a corresponding spiral portion of the contact carrier, the contact being provided with an inturned projection 72 (Fig. 6) which serves to position the contact on the contact carrier. 35 It will be observed that in this form of my switch mechanism the insulating contact carrier comprises a pair of cam wheels having spiral cams, and a circular flange extending above the cams and forming an insulating barrier between the contacts carried by the cam wheels.

The switch operating mechanism is so constructed that each pull of the pull chain 42 will move the commutator 39 through 180 degrees of movement.

As shown in Fig. 6 the cam wheels of the contact carrier 72 are each provided with a spiral cam portion 73 against which the spring contact fingers 68 and 68^a bear during a part of the movement of the contact carrier.

When the commutator is rotated from the position shown in Fig. 6 the contact fingers 68 and 68^a ride upon the surfaces of the spiral cams 73 and finally snap off from these spiral portions down into contact with the spirally curved contacts 29 and 30. During the next 180 degrees of movement, the spring fingers 68 and 68^a ride along the spiral contacts 29 and 30 and finally snap down off from the ends of the spiral contacts onto the spiral insulating portions 73.

The operation of the switch has been outlined in connection with the description of the construction.

When the switch is in "on" position, that is when the spring fingers 68 and 68^a are in engagement with the contacts 29 and 30, the circuit is from the wiring terminal 28, through the bracket portion 62, arm 70 63, contact portion of the contact 29, spring finger 68, base portion 66, spring finger 68^a, contact portion of the contact 30, arm 50, shaft 45, bearing member 46, bracket 48 and screw 49 to the center contact 26, thence 75 through whatever translating device is inserted in the receptacle, to the shell contact 25, and through the screw 36 to the wiring terminal 27.

Assuming that the parts are in positions 80 corresponding to that shown in Fig. 6 (in which the switch is in "off" position), the spring contact fingers 68 and 68^a being out of engagement with the contacts 29 and 30 and resting on the insulating spiral cam 85 portions 73 of the commutator, if it is desired to move the switch to "on" position, the chain 42 is pulled down until the projection 74 engages the shoulder 75 of the insulating base 31. This moves the lever 90 40 thru 180 degrees and also moves the commutator thru 180 degrees thru the intermediary of the ratchet mechanism 41. During this movement of 180 degrees, the spring contact fingers 68 and 68^a ride upon the 95 spiral portion 73 and at the end of the movement snap down simultaneously upon the contacts 29 and 30 respectively. This simultaneously makes a connection at two points, and completes the circuit between 100 the wiring terminal 28 and the center contact. The pull chain is then released, and the torsion spring 44 returns the switch lever 40 and pull chain 42 to their original position, the commutator however remaining stationary during this return movement 105 of the switch lever 40, the ratchet mechanism 41 permitting this return movement of the switch lever 40 without a corresponding movement of the commutator. The spring 110 fingers 68 and 68^a would resist a return movement of the commutator as the ends of these spring fingers would engage the shoulders at the end of the spiral cam portions 73, and would prevent a return movement 115 of the contact-carrier.

The return movement of the switch lever 40 under the action of the torsion spring 44 is limited by the engagement of the projection 74 with the shoulder 76 (Fig. 4).

If it is desired to move the switch from "on" to "off" position, the pull chain 42 is moved down to again move the lever 40 through an angle of 180 degrees. The pull chain is then released, and the torsion spring 44 again throws the switch lever back to its original position. During this movement of the switch lever 40, the commutator is advanced through another movement of 180 degrees, the commutator re- 125 130

maining stationary during the return of the switch lever. During this forward movement of 180 degrees of the commutator, the spring contact fingers 68 and 68^a ride upon 5 the spiral contact 29 and 30 respectively, and at the end of the movement these spring fingers 68 and 68^a snap off from the ends of the spiral contacts, thus making a quick simultaneous double break in the 10 circuit from the wiring terminal 28 to the center contact, thus breaking the arc at two points and greatly lessening the chances of injury to the contacts and other undesirable effects.

15 In the form of my invention shown in Figs. 12 to 20 inclusive the shell and center contacts 25 and 26, the wiring terminals 27 and 28, the electrical connecting member 30^a, the insulating base 31, the casing 20 32, the cap 33, the fibre lining 34, the fibre cover 35, the screw 36, the pull chain 42, the bracket 48, and the screw 49, which secures this bracket in place and electrically connects it with the center contact, may be 25 the same as in the form previously described, the main features of difference being in the switch mechanism itself.

The switch mechanism shown in this form 30 of my invention comprises a rotatably mounted commutator, including a contact 77, (which is always in electrical connection with the wiring terminal 28) a contact 78, (which is always in electrical connection with the center contact 26), and a built-up 35 contact-carrier 79, to which the contacts 77 and 78 are secured, and comprises also a built-up oscillatable switch operating member or lever 80, which as it is oscillated imparts a step by step movement to the 40 commutator, a ratchet mechanism 81 between the switch lever 80 and the commutator, and a coil torsion spring 82 for returning the oscillatable switch lever after it has been operated by the pull chain 42.

45 Many of the details of the switch mechanism are shown in perspective in an exploded view in Fig. 20. The built-up switch lever or operating member comprises a central spider like member 83 (Fig. 20) (having 50 an opening 84 through which the supporting shaft 85 extends) three discs 86, 87, and 88, which are slipped over the legs of the spider 83, and a spacer sleeve 89 which separates the discs 87 and 88 and is 55 also slipped over the spider. These discs 86, 87 and 88 are formed of suitable insulating material, such as sheets of fibre, and the sleeve 89 is also formed of insulating material. The spider 83 is also provided 60 with ratchet teeth 90 for engagement with cooperating ratchet teeth 91, stuck up from the arm 92 of the contact 78. The spider 83 may be a suitable sheet metal stamping, as may also be contacts 77 and 78. The pull 65 chain 42 is secured to the switch lever 80

by means of a hook member 93, (Fig. 20) having laterally extending lugs 94, which engage openings 95 and 96 respectively in the fibre discs 87 and 88.

The legs of the spider are provided with 70 outwardly projecting portions or lugs 97, to hold the insulating discs 86, 87 and 88 and the sleeve 89 in position on the spider.

In assembling the switch lever, the legs of the spider are bent inwardly enough to 75 permit the discs 86 and 87, the sleeve 89 and the disc 88 to be slipped over the outwardly extending projection 97. The ears 94 of the hook member 93 are inserted in the openings 95 and 96 respectively before 80 the discs 87 and 88 are moved up snugly against the ends of the sleeve 89. The discs 86, 87 and 88 are prevented from slipping off at one end by their engagement with the ratchet teeth 90 and are prevented 85 from slipping off at the other end by their engagement with the outwardly extending projections 97. In order to position the discs 86, 87 and 88 on the spider 83 and prevent relative rotation therebetween, each 90 of these discs is provided with a number of recesses 98 extending from its central opening, these recesses 98 being provided to receive the legs of the spider, when the parts are in assembled position. The chain 42 is 95 secured to the hook member 93 by engaging one of the balls in the hook portions, the shank which connects the balls lying in the space between the two hook members 99. The discs 86, 87 and 88 and the sleeve 89 100 fully insulate the pull chain 42 from the spider 83, (the disc 86 serving to cover up the end of the projection 94, which would otherwise be exposed). The switch lever 80 is supported at one end directly by the shaft 105 85 (which extends through the opening 84 of the spider), and is supported at its other end by a combined bearing and spring securing member 100 (Figs. 13 and 19) this member 100 having a cylindrical portion 110 101, which fits inside the legs of the spider 83, and extends through the opening in the disc 88, and thus forms a bearing for the spider and disc.

One end of the coil torsion spring 82 is 115 secured to the spider, as indicated at 102 in Fig. 17, and the other end of this coil torsion spring is secured to the member 100 as indicated at 103 in Fig. 13. The member 100 is adjustably mounted in the bracket 48 in 120 a manner similar to that in which the member 46 is mounted in the form of my invention previously described, the member 100 being provided with a struck-up portion 104, which can be made to engage in any one of 125 the notches in the bracket 48, the end of the member 100 being provided with a notch 105, to receive a screw-driver or other suitable tool. By inserting a screw-driver in this notch, and pressing the member 100 in. 130

wardly, until the lug 104 is disengaged from the notch in the bracket 48, the member 100 can be turned in either direction, to tighten or loosen the spring as may be desired, to give it the proper tension, and the screw-driver can then be withdrawn to permit the lug 104 to engage the proper notch in the bracket 48.

The built-up contact-carrier comprises 10 two similar ratchet shaped discs 106 of insulating material (see Fig. 20). One of these discs supports the curved contact 77 and the other supports the curved contact 78. This contact carrier also comprises a sleeve 108 of insulating material, (which is slipped over the shaft 85 and upon which the insulating discs are slipped), and a separating disc 109 of insulating material, also slipped on the sleeve 108, which serves to insulate the 15 contacts 77 and 78 from each other. The contact 77 is provided with an integral arm 110, extending inwardly, and having an opening through which the shaft 85 extends, this arm 110 serving to assist in holding the 20 contact in place on the contact-carrier, and also serving to electrically connect the contact with the wiring terminal 28. The insulating sleeve 108 extends through the opening in the bracket portion 62 of the wiring 25 terminal 28, and thus insulates the shaft 85 from this bracket portion, thus preventing a short circuit between the contact 78 and the wiring terminal 28.

The contacts are positioned on the discs 30 106 by means of an inturned lug 111 which engages a corresponding notch 112 which prevents the contact from slipping on its support.

The contact 77 is thus always in electrical 35 connection with the wiring terminal 28, through the arm 110 and the bracket portion 62. The contact 78 is always in electrical connection with the center contact, through its arm 92, shaft 85 or spider 83, 40 member 100, bracket 98 and screw 49.

In the "off" position of the switch, the contacts 77 and 78 are not electrically connected, being insulated from each other. In moving to the "on" position of the switch, 45 however, the spring fingers 68 and 68^a snap into engagement with the contacts 77 and 78 respectively and establish electrical connection therebetween. When the switch is moved from "on" to "off" position the spring 50 fingers 68 and 68^a snap off of the rear ends of the contacts 77 and 78 respectively and thus break the electrical connection therebetween simultaneously at two points, as in 55 the form previously described, thus dividing the arc.

The movement of the switch lever 80 is 60 limited to 180 degrees by means of a projection 113 on the disk 88 which engages the shoulder or abutment 75 to limit the 65 movement in one direction, and engages the

shoulder 76 to limit the movement in the other direction.

Having thus described my invention, what I claim as new and desire to secure by Letters Patent is:

1. A switch comprising a base, a movably mounted contact carrier of insulating material supported by said base, two contacts of conducting material mounted on said contact carrier and insulated from each other in the "off" position of the switch, a barrier between said contacts for preventing short circuiting therebetween, and bridging means of conducting material also carried by said base and arranged to be engaged by both of said contacts in their movement, and with respect to which both of said contacts also move out of engagement in their movement, whereby said contacts are alternately connected and disconnected electrically with respect to each other by means of said bridging means, said bridging means being provided with a pair of contact tongues straddling said barrier.

2. A switch comprising a rotatably mounted commutator, having two spiral insulating portions lying alongside each other, and two spiral conducting portions lying alongside each other, said spiral conducting portions being insulated from each other in the "off" position of the switch, and bridging means of conducting material with which both of said conducting portions make contact in their movement, and with respect to which both of said insulating portions also make contact in their movement, said bridging means being provided with two contact fingers, said fingers being arranged to snap off said conducting portions on to said insulating portions to break the circuit at two points simultaneously and to snap off said insulating portions on to said conducting portions to make the circuit at two points simultaneously.

3. The combination of an insulating base, a rotatably mounted insulating member carried thereby, ratchet means for rotating said member, a pair of switch contacts carried by said insulating member, bearings for said member arranged to have rubbing electrical connection with said contacts, means for making electrical connection with said bearings and a stationary bridging member carried by said base and arranged to connect and disconnect said contacts and thereby make and break the circuit through the same and electrically connect and disconnect said bearings.

4. A switch socket comprising an insulating base, a wiring terminal and receptacle contact supported on said insulating base, a rotatably mounted insulating member carried thereby, ratchet means for rotating said member, a pair of switch contacts carried by said insulating member, bearings for said

6 insulating member having electrical connection with said contacts, one of said bearings being electrically connected to said wiring terminal, and the other of said bearings being electrically connected to said receptacle contact, and a stationary bridging member arranged to connect and disconnect said

switch contacts, and thereby make and break the circuit through the same, and electrically connect and disconnect said bearings.

10 In witness whereof, I have hereunto subscribed my name.

CHARLES L. HOPKINS.
